PORABLE HEATER

Francisco Beldarrain, Cordovilla-Pamplona, Spain,
assignor to Orbaiceta S.A., Cordovilla, Spain

Filed Dec. 18, 1972, Ser. No. 315,843

Term of patent 14 years

Int. Cl. D23—03

U.S. Cl. D23—123

Fig. 1.

Fig. 2

FIG. 1 is a front perspective view of a portable heater showing my new design.

FIG. 2 is a rear perspective view thereof.

The side opposite the handle and the bottom are plain and flat.

I claim:

The ornamental design for a portable heater, substantially as shown and described.
